UNITED STATES PATENT OFFICE

93,572

DESIGN FOR A FAMILY ALTAR

Boleslaw Podbielski, Norristown, Pa.

Application March 15, 1934, Serial No. 51,053

Term of patent 7 years

To all whom it may concern:

Be it known that I, BOLESLAW PODBIELSKI, a citizen of the United States, residing at Norristown, in the county of Montgomery and State of Pennsylvania, have invented a new, original, and ornamental Design for a Family Altar, of which the following is a specification, reference being had to the accompanying drawing, forming part thereof.

The leading feature of my design consists of an altar having three niches surmounted by crosses. The niches "A", are of a depth and height suitable to receive a statuette of a saint, crucifix or similar religious emblem.

In the accompanying drawings:

Fig. 1 is a front elevation of the family altar showing my new design; and

Fig. 2 is a side elevation thereof.

Fig. 3 is a perspective showing side of horizontal and vertical bars having a plurality of grooves.

Fig. 4 is a perspective showing end of horizontal bars.

I claim:—

The ornamental design for a family altar as herein shown and described.

In testimony whereof, I affix my signature.

BOLESLAW PODBIELSKI.
